UNITED STATES PATENT OFFICE

153,711

DESIGN FOR A FORK OR OTHER ARTICLE OF FLATWARE

Isadore Albert Lipman, Meriden, Conn., assignor, by mesne assignments, to Amston Silver Company, Inc., Amston, Conn., a corporation of Connecticut

Application November 16, 1948, Serial No. 149,672

Term of patent 14 years

(Cl. D54—12)

To all whom it may concern:

Be it known that I, Isadore Albert Lipman, a citizen of the United States, residing in Meriden, in the county of New Haven and State of Connecticut, have invented a new, original, and ornamental Design for a Fork or Other Article of Flatware, of which the following is a specification, reference being had to the accompanying drawing, forming part thereof, in which

Fig. 1 is a face view of a fork, showing in full lines the essential features of my new design; and

Figs. 2, 3 and 4 are sections, respectively, on lines 2—2, 3—3 and 4—4 of Fig. 1.

I claim:

The ornamental design for a fork or other article of flatware, substantially as shown and described.

ISADORE ALBERT LIPMAN.
